(57) **CLAIM**

We claim the ornamental design for a hummingbird feeder component, as shown and described.

DESCRIPTION

FIG. 1 is a front, top perspective view of a hummingbird feeder component in a first configuration, in accordance with the present invention;

FIG. 2 is a front elevation view of the hummingbird feeder component of FIG. 1 in the first configuration;

FIG. 3 is a rear elevation view of the hummingbird feeder component of FIG. 1 in the first configuration;

FIG. 4 is a left elevation view of the hummingbird feeder component of FIG. 1 in the first configuration;

FIG. 5 is a right elevation view of the hummingbird feeder component of FIG. 1 in the first configuration;

FIG. 6 is a top plan view of the hummingbird feeder component of FIG. 1 in the first configuration;

FIG. 7 is a bottom plan view of the hummingbird feeder component of FIG. 1 in the first configuration;

FIG. 8 is a front, top perspective view of the hummingbird feeder component of FIG. 1 in a second configuration, in accordance with the present invention;

FIG. 9 is a front elevation view of the hummingbird feeder component of FIG. 1 in the second configuration;

FIG. 10 is a rear elevation view of the hummingbird feeder component of FIG. 1 in the second configuration;

FIG. 11 is a left elevation view of the hummingbird feeder component of FIG. 1 in the second configuration;

FIG. 12 is a right elevation view of the hummingbird feeder component of FIG. 1 in the second configuration;

FIG. 13 is a top plan view of the hummingbird feeder component of FIG. 1 in the second configuration; and,

FIG. 14 is a bottom plan view of the hummingbird feeder component of FIG. 1 in the second configuration.

The broken lines shown herein are for illustrative purposes and form no part of the claimed design. In FIGS. 1-6 and 8-13, the broken lines in the form of an alternating series of relatively short dashes and relatively long dashes represent the bounds of the claimed design.
